TAILSTOCK LOCK

William M. McConnell, McKeesport, Pa., assignor
to Mackintosh-Hemphill Company, Pittsburgh,
Pa., a corporation of Delaware

Application August 14, 1943, Serial No. 498,691

8 Claims. (Cl. 82—31)

This invention relates to tail-stock clamping devices, especially those that are useful in heavy duty engine lathes wherein the thrust exerted upon the tail-stock is great, which necessitates the use of means of great strength and holding power to secure the tail-stock against accidental displacement during operation of the lathe.

The common, or conventional, structure of engine lathes comprises as elements a face-plate which is mounted and rotatably driven at a head-stock which provides driving connections for the face-plate; a center-post carried by the face-plate and providing a live center for the work; and a tail-stock mounted in the lathe bed and including a static center for the work in opposition to the live center carried by the face-plate. The tail-stock, with its static-opposed center, conventionally is adjustable across the lathe bed for accurate alignment with the live center which is carried by the head-stock of the lathe. The base in which the tail-stock is thus mounted is adjustable longitudinally of the lathe bed toward and away from the live center to bring its center functionally into opposition on the work.

One primary object of my invention is to provide in association with the tail-stock of an engine lathe, a clamping assembly which is so sturdy and effective that it is capable of sustaining heavy loads and is capable of clamping the tail-stock securely to the bed of the lathe in accurate alignment with the live center carried by the face-plate.

Another object of the invention is to provide a clamping organization for the base structure of a lathe tail-stock such that the elements acted upon in loosening and tightening clamping engagement are easily accessible, and such that none of these elements need be removed from assembly in making adjustment of the tail-stock.

Another object of my invention is to provide a clamping assembly of that identified sort which functions effectively, without requiring any specialized structure or form of the lathe bed to which it clamps the tail-stock.

In the accompanying drawings:

Fig. I is a vertical longitudinal sectional view through the tail-stock of an engine lathe and the mounting structure therefor, showing the novel clamping assembly of my invention.

Fig. II is a rear view of the tail-stock assembly shown in Fig. I, taken partly in elevation and partly in vertical section on the section line II—II of Fig. I, showing the side rails of the lathe bed on which the tail-stock is mounted.

Fig. III is a detail perspective view of one pressure member of the clamping assembly.

Fig. IV is a detail perspective view of the other pressure member of the clamping assembly.

Fig. V is a detail perspective view of a clamping member, cooperative with the pressure members of Figs. III and IV.

Describing the drawings in detail, the lathe bed includes two transversely spaced, horizontal side rails 1 and 2, having top surfaces 3 which form ways for slidably supporting the tail-stock, vertical facing surfaces 4, and bottom surfaces 5. All of these surfaces are machined to smooth planes arranged in accurately spaced and correct angular relation. The tail-stock assembly of the lathe includes a base 6 having longitudinally spaced pairs of supporting surfaces 7 that rest slidably on the upper surfaces 3 of the side rails. Base 6 has portions 8 which extend downwardly between the transversely spaced side rails of the lathe bed. The downwardly extended portions 8 have vertical surfaces 9, arranged to contact and bear against the opposed vertical surfaces 4 of the rails.

25 In order to clamp the tail-stock base rigidly, both transversely and longitudinally of the lathe, so that alignment of the tail-stock center with the live center of the head-stock may be maintained accurate when the lathe is working, I

30 have provided an assembly for clamping the tail-stock base in a transverse direction against the vertical surfaces 4 of one of the rails. The downward extensions 8 of the tail-stock base carry two clamping members 10 that may be 35 formed integral with the base, but which are preferably attached blocks, as shown, that are set into the base and secured as by bolts 11. The pair of clamping members 10 are placed one at each end of the tail-stock base, and are both acted upon 40 by a pair of longitudinally extended pressure bars.

One longitudinal side 12 of each of the clamping members 10 is beveled downwardly and toward the longitudinal center line of the lathe bed, to provide the inwardly declining contact surface 13. The other longitudinal side 14 of each clamping member has a rectangular chamfer 15 at its lower edge.

The two pressure bars 16 and 17 extend longitudinally of the lathe bed in cooperative relation with the clamping members 10 and the side rails 1 and 2. Pressure bar 16, one of the duplicate ends of which is shown, is formed in each of its end regions in which it cooperates with 55 one of the clamping members 10, with one up-

wardly and outwardly beveled side surface 13. The other side surface in each of the end regions of the pressure bar 16 has a rectangular chamfer 19 at its upper edge. In each of its end regions the pressure bar is pierced by a bolt hole 20. As shown in Fig. III pressure bar 16 is cut in between its end regions along one side of the bar, and it is to be understood that it may similarly be cut in between end regions at the other side of the bar. Because the contact surfaces of the pressure bar are needed only in its end regions, the elimination of metal between those regions lessens the weight of the bar and economizes material.

The other pressure bar 17 has rectangular chamfers 21 and 22 extended along its upper side edges. The structure of this pressure bar, also, may be cut away between end regions which cooperate with the two clamping members 10 at the ends of the tail-stock base. This may be done to eliminate at least the chamfered structure of the pressure bar between its end regions, with consequent decrease in weight and saving in material. In each end region of the pressure bar there is an elongate bolt hole 23 arranged with its major axis extended transversely of the pressure bar.

In assembly the end regions of the pressure bars are brought into cooperative relation with the two clamping members 10, the organization of these elements being shown clearly in Fig. II of the drawings. In such organization the pressure bars 16 and 17 are adjustably supported respectively by two pairs of king bolts 24 and 25, which pass through the tail-stock base and the bolt holes 20 and 23 of the pressure bars and the heads of which bear against the under surfaces of the pressure bars. As so supported the upwardly and outwardly chamfered faces in the end regions of pressure bar 16 cooperate with the inwardly declining contact surfaces 13 of the clamping members 10, and the chamfered regions 19 of the pressure bar engage the corner of one side rail 1 at the junction of its side face 4 and bottom face 5. The other pressure bar 17 has its chamfered regions 21 underlying the clamping members 10 in their chamfers 15, and has its other chamfered regions 22 embracing the inwardly presented side face 4 and bottom face 5 of the second side rail 2.

Fig. II of the drawings shows the tail-stock base clamped to the lathe bed. To bring the clamping assembly into that condition it is necessary merely to tighten up on nuts 24a and 25a, which are threaded on the shanks of bolts 24 and 25 and bear through washers upon the upper surface of bottom plate 26 of the tail-stock structure. This action, which is had on all the four king bolts, draws both ends of both the pressure bars 16 and 17 upward, and forces the surfaces in their chamfered regions into firm engagement with the under surfaces 5 of that one of the side rails 1 and 2 which respectively stands adjacent each pressure bar. Also upward movement of pressure bar 16 causes its sloping contact surfaces 18 to move cooperatively with the sloping contact surfaces 13 of the clamping members 10. This cooperative effect propels the tail-stock base as a whole away from the side rail 1 to which the pressure bar 16 is adjacent, and toward the other side rail 2 until the vertical surfaces 9 on extensions 8 of the tail-stock base are forced firmly against vertical surfaces 4 of the side rail. The tail-stock base is thus clamped to the lathe bed by pressure of the pressure bars

16 and 17 upwardly against the under surfaces of the side rails 1 and 2, and the tail-stock base itself is forced firmly against the side rail 2. Desirably the downward extensions 8 of the tail-stock base have a loose fit between the side rails 1 and 2, with merely enough clearance between the side surfaces 9 and the vertical contact surfaces of the side rails to permit the tail-stock structure as a whole, to slide on the rails in making adjustments of the tail-stock longitudinally of the lathe bed. Slight tightening action of nuts 24a and 25a on the bolts 24 and 25 is therefore adequate to exert a great clamping force on the tail-stock base, holding it in fixed position against the operating forces of the lathe.

It is possible to resolve each of the pressure bars into two clamping blocks, each cooperative with one of the clamping members 10. There is advantage, however, in utilizing pressure bars which provide continuous structures extended between the clamping members. This is for the reason that the bolts at the opposite ends of the tail-stock base frequently are not drawn up at exactly the same instant of time. The physical continuity of the pressure bars counteracts the tilting tendency which otherwise results from lack of absolute synchronism in drawing-up at the opposite ends of the tail-stock base. If desired, the two clamping members 10 may be resolved into a single structure continuous from end to end of the tail-stock base, and such modification is indicated if the tail-stock base is relatively short. As a refinement, the bolts 24 have their heads tapered as at 28 to fit cooperatively tapered seats in the underbody of pressure bar 16. This tends to give a direct upward pull on the pressure bar in drawing-up on the bolts.

Transverse adjustment of the tail-stock is made without disturbing the clamped engagement of the tail-stock base with the lathe bed. As appears in Fig. II of the drawings, the bolts 24 and 25 pass through transversely elongate holes 29 in the bottom plate 26 of the tail-stock structure, so that this structure may be moved on the tail-stock base 6 and may be clamped in adjusted position by suitable elements associated with it.

Adjustment of the tail-stock base, and the tail-stock carried by it, longitudinally of the lathe bed is permitted by retracting nuts 24a and 25a on the bolts 24 and 25. This permits the pressure bars 16 and 17 to drop away from the under surfaces of the side rails 1 and 2 the distance permitted by increased extension of the bolts 24 and 25 below the bottom of the tail-stock base, and frees the clamping members 10 from the forcing action of pressure bar 16. The clamping effect which locks the tail-stock base to the lathe bed is thus released and longitudinal movement of the base is made possible. It is to be noted that release of the clamping effect and its subsequent restoration does not involve the removal and replacement of any element of the clamping assembly, but that all elements of the clamping assembly are loosened, or freed, while leaving them in their assembly relation and in condition to be again brought into their clamping engagements. This advantage is of great value in association with the tail-stock of an engine lathe, because the removal and replacement of parts within the rigidly confined space embraced in the lathe bed would present a problem of major importance. It is to be noted, also that in the organization all beveled and chamfered surfaces are carried by the smaller ele-

ments of the clamping assembly, thus avoiding the difficulty involved in beveling and chamfering the side rails of the lathe bed. The combination of the forces directed both upwardly and transversely against the side rails of the lathe bed gives a clamping effect of particular firmness which, together with the structural strength of the elements involved in the clamping, holds the tail-stock accurately in position against the exertion of the forces which are encountered in operation of a heavy duty engine lathe.

Several structural modifications have been above suggested. It is to be understood that those and various other modifications may be made while remaining within the scope of my invention as defined in the appended claims.

I claim as my invention:

1. In combination with a lathe bed having parallel spaced side rails and a tail-stock base mounted between the said side rails for movement along the lathe bed, a clamping assembly including a clamping member dependent from the tail-stock base, a pair of through-bolts extended through the tail-stock base, pressure members carried respectively by the said through-bolts in position each to underlie respectively the said clamping member and one of the side rails of the lathe bed, one of the said pressure members and the said clamping member having cooperatively beveled lateral faces, so that pressure exerted by the said through-bolts forces the pressure members of the assembly against the under faces of both the said side rails and forces the tailstock base laterally against one of the said side rails.

2. In combination with a lathe bed having parallel spaced side rails and a tail-stock base mounted between the said side rails for movement along the lathe bed, a clamping assembly including a clamping member dependent from the tail-stock base, a pair of through-bolts extended through the tail-stock base, pressure members carried respectively by the said through-bolts in position each to underlie the said clamping member and one of the side rails of the lathe bed, both the said pressure members being formed to have a square-shouldered engagement each with one of the said side rails, one of the said pressure members and the said clamping member having cooperatively beveled lateral faces, so that pressure exerted by the said through-bolts forces the pressure members of the assembly against the under faces of both the said side rails and forces the tail-stock base laterally against one of the said side rails.

3. In combination with a lathe bed having parallel spaced side rails and a tail-stock base mounted between the said side rails for movement along the lathe bed, a clamping assembly comprising a clamping member dependent from the said tail-stock base and having a beveled lateral face, a separate pressure member having a lateral face cooperatively beveled with respect to the beveled lateral face of the said clamping member and underlying one side rail of the lathe bed, and means organized with the said separate pressure member to force the said member upwardly against the side rail which it underlies and by the cooperation of its beveled lateral face with the beveled lateral face of the clamping member to force the tail-stock base laterally against the other side rail of the lathe bed.

4. In combination with a lathe bed having parallel spaced side rails and a tail-stock base

mounted between the said side rails for movement along the lathe bed, a clamping assembly comprising a clamping member dependent from the said tail-stock base and having a beveled lateral face, a separate pressure member having a lateral face cooperatively beveled with respect to the beveled face of the said clamping member and underlying one side rail of the lathe bed, means organized with the said separate pressure member to force that member upwardly against the side rail which it underlies and by the cooperation of its beveled face with the beveled face of the clamping member to force the tail-stock base laterally against the other side rail of the lathe bed, and a second pressure member mounted and arranged to be forced upwardly against the said last-named side rail.

5. In combination with a lathe bed having parallel spaced side rails and a tail-stock base mounted between the said side rails for movement along the lathe bed, a clamping assembly comprising two laterally beveled clamping members dependent from the tail-stock base and spaced from each other longitudinally of the tail-stock, a separate pressure bar extended longitudinally of the tail-stock having a lateral face beveled cooperatively with the cooperative lateral bevels of the said clamping members and underlying one side rail of the lathe bed, and means organized with the said separate pressure bar to force the said member upwardly against the side rail which it underlies and by the cooperation of its beveled lateral face with the lateral bevels of the clamping members to force the tail-stock base laterally against the other side rail of the lathe bed.

6. In combination with a lathe bed having parallel spaced side rails and a tail-stock base mounted between the said side rails for movement along the lathe bed, a clamping assembly comprising two laterally beveled clamping members dependent from the tail-stock base and spaced from each other longitudinally of the tail-stock, a separate pressure bar extended longitudinally of the tail-stock having a lateral face beveled cooperatively with the cooperative lateral bevels of the said clamping members and underlying one side rail of the lathe bed, means organized with the said separate pressure bar to force the said member upwardly against the side rail which it underlies and by the cooperation of its beveled lateral face with the lateral bevels of the clamping members to force the tail-stock base laterally against the other side rail of the lathe bed, a second pressure bar underlying both the said clamping members, and means organized to force the said second pressure bar upwardly against that side rail against which the tail-stock base is forced.

7. In combination with a lathe bed having parallel spaced side rails and a tail-stock base mounted between the said rails for movement along the lathe bed, a clamping assembly comprising clamping structure dependent from the tail-stock base and presenting toward one of the said side rails two beveled lateral faces spaced from each other longitudinally of the tail-stock, a separate pressure bar extended longitudinally of the tail-stock having a lateral face beveled cooperatively with the cooperative lateral bevels of the said dependent clamping structure and underlying one side rail of the lathe bed and abutting one edge thereof, and means organized with the said separate pressure bar to

force the said member upwardly against the side rail which it underlies and by the cooperation of its beveled lateral face with the lateral beveled faces of the said clamping structure to force the tail-stock base laterally against the other side rail of the lathe bed.

8. In combination with a lathe bed having parallel spaced side rails and a tail-stock base mounted between the said rails for movement along the lathe bed, a clamping assembly comprising clamping structure dependent from the tail-stock base and presenting toward one of the said side rails two beveled lateral faces spaced from each other longitudinally of the tail-stock, a separate pressure bar extended longitudinally of the tail-stock having a lateral

face beveled cooperatively with the cooperative lateral bevels of the said dependent clamping structure and underlying one side rail of the lathe bed and abutting one edge thereof, means organized with the said separate pressure bar to force the said member upwardly against the side rail which it underlies and by the cooperation of its beveled lateral face with the lateral beveled faces of the said clamping structure to force the tail-stock base laterally against the other side rail of the lathe bed, a second pressure bar underlying the said dependent clamping structure, and means organized to force the said second pressure bar upwardly against that side rail against which the tail-stock base is forced.

WILLIAM M. McCONNELL.
